COMPRESSOR VALVE

Joseph Frank Kowacz, Regina, Saskatchewan,
Canada

Application September 21, 1940, Serial No. 357,811

3 Claims. (Cl. 251—146)

This invention relates to compressor valve structure and in particular to compressor outlet valve structure. Objects of the invention are to provide a light and efficient valve particularly suitable for use in high speed machines, to provide improved guide means for the valve, to provide an arrangement wherein parts subjected to the greatest wear are readily replaceable, and to provide an improved breather arrangement for the guide means. The manner in which these and other objects are accomplished will be described with reference to the accompanying drawings which show the invention in illustrative embodiment. In the drawings:

Figure 1 is a section on line 1—1 of Figure 2 of valve structure in accordance with the invention;

Figure 2 is a section substantially on line 2—2 of Figure 1;

Figure 3 is a section substantially on line 3—3 of Figure 1;

Figure 4 is an enlarged view partly in elevation and partly in section of a valve and valve guiding means appearing in Figures 1 and 2, and

Figure 5 is an axial section of the valve and valve guiding means.

Referring to the drawings, the valve cage comprises a cylindrical block 10 provided, as here shown, with five symmetrically disposed through openings 11. Each opening, as shown in Figure 1, comprises a cylindrical upper portion 12, a conical bottom shoulder 13 of which the portion 14 comprises the valve seat, and a cylindrical extremity 15.

The valve guiding means, generally designated by the reference numeral 16, comprises inner and outer cylindrical members 17 and 18 which are threaded together at their upper ends, at 19, in concentric relation with a narrow annular space 20 between them. Member 18 is provided with external axially extending ribs 21 which project below the cylindrical portion and have inclined ends complementary to the inclination of the shoulder 13. The lower extremities of the ribs 21 have inner surfaces flush with the inner walls of the cylinder.

The inner member 17 is provided with an end wall 22 which has a central breather hole 23. Beneath wall 22 the bore of member 17 is restricted at 24 so as to engage and retain one end of a compression spring 25 which bears against wall 22.

Reference numeral 26 designates a cup-shaped valve having an imperforate head 27 and a cylindrical skirt 28 which is received with a close

sliding fit, both inside and out, in the annular space 20. The lower end of spring 25 bears against the head 27, and the latter has a conical portion 29 for cooperation with seat 14, there being an extension 30 below the portion 29.

With the guide means and valve assembled, as shown in Figures 4 and 5, the assembly is pressed into an opening 11 until the lower ends of ribs 21 abut shoulder 13, the ribs closely engaging the walls of the opening 11 so that the assembly is frictionally maintained in coaxial relation with seat 14 against which the valve 26 is pressed by the spring 25. In this relation of parts, the extension 30 projects below seat 14, which terminates somewhat above the lower face of block 10 so as to provide a seat of adequate strength, so that the closed end of the head 27 is substantially flush with the bottom surface of the block. In this manner, a substantially flat upper boundary is provided for the compression chamber. The top of the guide unit is substantially flush with the top face of the block 10.

Reference numeral 31 designates a circular cap plate which, as here shown, has integral therewith five tubular members 32 in the form of inverted frusta. Also depending from the plate are four legs in the form of webs 33 whose lower ends are all in the same plane with the lower ends of elements 32. As here shown, the cap 31 is secured on top of block 10 by means of four cap screws 34, and with the parts thus associated, the passages 32' of elements 32 are in register with the breather holes 23 of the valve guiding units, these passages being continued

35 through the cap plate 31.

Reference numeral 35 designates a cylinder provided with a shoulder 36 on which block 10 rests. The cylinder is provided with a cover plate 37 between which and cap plate 31 a compression spring 38 is interposed, the lower end of the spring being centered by an annular rib 39 on the top of plate 31. The cylinder has an outlet opening or openings in the zone between block 10 and cap plate 31.

On the compression stroke the valves 26 move upwardly, permitting gas to flow upwardly through the openings defined between ribs 21. Upward movement of the valves gives rise to a compression effect in the guides, this being relieved through the breather holes 23 which are in communication through the tubular compression members 32 with the cylinder chamber above cap 31. A desirable dash pot effect, controlled in dependence upon the size of the breather

holes 23, is secured on both opening and closing movements of the valves.

The valves are positively guided by the inner and outer surfaces, and consequently accurate seating and long wear are afforded. The lower extensions of ribs 21 constitute parts of the outer guide surfaces. The seats 14 in ordinary use will wear practically indefinitely, the guide units and valves being replaceable as frequently as required. The valves themselves are very light 10 and thus adapted for the most rapid operation. Long-life precision operation of the valves is contributed by the imperforate sliding and duplicate guiding surfaces.

It will be understood that depending on the 15 capacity of the compressor, one or more valves may be utilized under the invention, and five have been shown here merely by way of example. Also it will be understood that the invention is not necessarily limited to the described 20 details of construction, and consequently I do not limit myself in these matters except as in the following claims.

I claim:

1. Compressor outlet valve structure comprising a cage, said cage comprising a block having a through opening, a valve seat on said block at one end of said opening, a valve guide unit in said opening behind said seat, said guide unit comprising nested inner and outer cylindrical 30 members separably secured together in concentric relation with a narrow annular space be-

tween them, and axially extending ribs on the outside of said outer member frictionally engaging the walls of said opening to maintain said unit coaxial with said seat; and a cup-shaped 5 valve having a head portion cooperable with said seat and having a cylindrical skirt portion slidably guided in said annular space.

2. Apparatus according to claim 1 wherein said seat is extended to provide an abutment surface for the adjacent ends of said ribs, which ends project beyond the cylindrical portion of said outer member.

3. In combination, a cage comprising a block having a through opening, a valve seat on said block at one end of said opening, valve guide means in said opening behind said seat, abutment means limiting insertion of said guide means toward said seat, said guide means including a wall remote from said seat having a breather hole; a valve cooperating with said seat and having a portion guided by said guide means, movements of said valve causing breathing through said hole; and means for holding said guide means against said abutment means, said holding means comprising a cap member, a tubular compression member extending between said cap member and said guide member and connecting said hole with an aperture in said cap, and means maintaining said members in operative association.

JOSEPH FRANK KOWACZ.
